UNITED STATES PATENT OFFICE.

WILLIAM H. TAYLOR, OF BALTIMORE, MARYLAND, ASSIGNOR, BY DIRECT AND MESNE ASSIGNMENTS, TO UNITED SHOE MACHINERY COMPANY, OF PATERSON, NEW JERSEY, A CORPORATION OF NEW JERSEY.

HEEL FOR BOOTS AND SHOES.

No. 834,085.

Specification of Letters Patent.

Patented Oct. 28, 1906.

Application filed January 7, 1904. Serial No. 188,108.

To all whom it may concern:

Be it known that I, WILLIAM H. TAYLOR, a citizen of the United States, residing at Baltimore, Maryland, have invented certain new and useful Improvements in Heels for Boots and Shoes, of which the following is a specification.

This invention relates to boots or shoes, and more particularly to heels for boots and shoes.

It has for its general object to provide an improved construction of heel which will permit heels of the class hereinafter referred to be firmly secured to boots or shoes.

Where the several lifts of a heel are attached to a shoe by nails driven in a direction perpendicular to the lifts, certain forms of heels cannot be attached securely. Examples of these are found more particularly in the tapered or curved heels of ladies' shoes in which the top lift and outer lifts may be of considerably less area than the heel-seat lift and in which it may be desirable to undercut the rear or to hollow the breast of the heel. When the nails to secure these forms of heels are driven in a direction perpendicular to the lifts, considerable portions of some of the lifts remain unperforated by the nails, and as a result the heels are insecurely attached.

It is the object of the present invention to avoid this objection and so to attach the heel that it will be firmly secured in place.

My invention consists in a boot or shoe in which this result is obtained by inserting the nails in the heel in a position inclined from the tread-face of the heel toward the rear of the heel, the inclination of the nails being uniform, so that they lie in a parallel relation and the nails being arranged over substantially the entire area of the tread-face of the heel. Preferably the nails are driven through the heel into the heel-seat of the shoe, and their points are clenched toward the rear of the heel. A top lift may be secured to the heel by being spanked on the ends of the inclined nails, which may project from the face of the heel for this purpose.

The drawing shows in section a portion of a shoe embodying my invention and also parts of a machine which may be employed in attaching the heel.

The machine, parts of which are shown in

the drawing, is not claimed in this application, it being embraced in my applications, Serial Nos. 188,109 and 219,981, filed January 7, 1904, and August 8, 1904, respectively.

In the drawing, A represents a heel of a form commonly applied to ladies' shoes. As will be observed, this heel is of considerable height, and its rear is undercut and the breast hollowed, the dotted line indicating the degree of concavity of the breast. The heel A is held on the sole 4 by nails 5, which are arranged so as to hold firmly all parts of the heel and prevent any opening between lifts, which would detract from the appearance of the heel. It will be apparent that with the form of heel shown the rear of the heel would be insecurely attached by nails passing through the heel in a direction perpendicular to the lifts. I have accordingly given the nails 5 such an inclination as to conform substantially to the slant of the heel. As shown, the nails have a position inclined from the tread-face of the heel toward the rear of the heel, the inclination of the nails being uniform, so that they lie in a parallel relation.

In the preferred embodiment of the invention the nails are driven from the outside of the shoe, passing through the heel into the heel-seat of the shoe. It is desirable to clench the points of the nails toward the rear of the heel, since such an arrangement permits the ends of the nails to be clenched without liability of fracture, and also because the bent-over points of the nails in this position are less liable to be raised from contact with the inner face of the insole.

It will be apparent from the drawing that the inclination given the nails also permits the breast to be hollowed as desired. Where the nails are perpendicular to the lifts, this operation of hollowing the breast is often interfered with on account of the proximity of the nails to the breast. The stroke of the drivers 6 in the machine above referred to may be adjusted to leave the ends of the nails projecting above the face of the heel to secure a top lift 2 to the heel. The inclination of the nails 5 is also advantageous in connection with the use of a top lift, since it permits the nails to be located nearer the breast of the top lift, and hence allows the top lift to be secured more firmly than is the

case where it is spanked on nails perpendicularly arranged. Furthermore, the inclined ends of the nails embedded in the top lift provide a more effective securing means than 5 nails having their ends perpendicular to the top lift.

Having described my invention, what I claim as new, and desire to secure by Letters Patent of the United States, is—

- 10 1. A heel provided with a set of nails inserted at intervals over substantially the entire area of the tread-face of the heel, said nails being inclined from said face of the heel toward the rear of the heel, and a top lift spanked on the ends of the inclined nails.
- 15 2. In a boot or shoe, a heel comprising a series of lifts secured to the boot or shoe by nails having a uniform inclination from the

tread-face of the heel toward the rear of the heel, said nails being arranged over substantially the entire area of the tread-face of the heel.

3. In a boot or shoe, a heel secured to the boot or shoe by nails inserted at intervals over substantially the entire area of the 25 tread-face of the heel and driven in a direction inclined from the tread-face of the heel toward the rear of the heel, and having their points clenched toward the rear of the heel.

In testimony whereof I affix my signature 30 in presence of two witnesses.

WILLIAM H. TAYLOR.
